UNITED STATES PATENT OFFICE.

ASAPH MERRIAM AND CHARLES L. LITTLE, OF WEST MERIDEN, CONN.

DESIGN FOR PINCUSHIONS.

Specification forming part of Design No. 7,081, dated December 30, 1873; application filed December 15, 1873.
[Term of Patent 7 years.]

To all whom it may concern:

Be it known that we, ASAPH MERRIAM and CHARLES L. LITTLE, of West Meriden, in the county of New Haven and State of Connecticut, have invented a Design for Pincushions, of which the following is a specification:

The nature of our design is fully represented in the accompanying photographic illustration, to which reference is made.

A represents a pincushion. This cushion is contained in a cup, *a*, with scalloped edge, the sides of the cup being ornamented in relief, as shown in said photograph. The cup *a* is joined, by a neck, *f*, to a base, *b*, having three supporting-legs, *c*, each of these legs being ornamented in relief. Midway between the legs is a scallop, *d*, projecting downward, and ornamented in relief, and immediately above the scallop *d* is cast in relief a medallion bust, *e*, surrounded by a circle, and ornamented on

each side with leaves, all in high relief. That part of the base of the cushion extending from the neck to the legs is convex, so that it and the cup have a shape not unlike an hour-glass; the whole forming a neat and attractive design for a pincushion, the distinctive features of which are the cup and support of a pincushion formed and ornamented as shown and described in the foregoing description and accompanying photograph.

What we claim as new, and desire to secure by Letters Patent, is—

A design for a pincushion, substantially as shown and described.

ASAPH MERRIAM.
CHAS. L. LITTLE.
